NOISE ELIMINATOR FOR LEVER ACTION OF
GRAND PIANOS

Julius Tusty, Sr., New York, N. Y.

Application January 17, 1938, Serial No. 185,253

3 Claims. (Cl. 84—216)

This invention relates broadly to control devices for piano actions, and especially to a control device for the lever action of grand pianos, and to means for eliminating noises caused by such device.

The prime object of my invention is to provide, in connection with a lever for shifting piano actions of grand pianos, means whereby the lever portion engaging the support of the piano action will be constantly in operative engagement with said support.

Another object of my invention is to provide, with a lever end engaging the support of the piano action of grand pianos, resilient means for constantly keeping said lever portion in forcible, tensional engagement with said support, in order to eliminate noises resulting from the operation of this lever portion.

The foregoing and still further objects and advantages of my invention will become more fully apparent from the ensuing description, in connection with the accompanying drawing, which latter, although shown in a more or less diagrammatical form, is intended for explanatory purposes only, without limiting my invention to the actual showing, and in which drawing

Fig. 1 illustrates a perspective view of a piano action support and its operating mechanism, the latter in accordance with my invention.

Fig. 2 is an enlarged cross-sectional view taken on lines 2—2 of Fig. 1.

Fig. 3 is a bottom view of a portion of the piano action support, showing the operating slot, and the action operating lever, including my improvements, engaging the slot.

Fig. 4 is a perspective view of my improved device in its preferred form.

Fig. 5 is a top view thereof, and

Fig. 6 shows a top view of a modified form of my device.

Referring now specifically to Figs. 1, 2 and 3, numeral 10 denotes a support for the piano action, which latter is indicated at 11 in Fig. 2. This piano action support is preferably provided at its bottom with friction reducing means 12, resting against a friction reducing rail 13 embedded in the housing 14 of the piano. The long sides of support 10 are preferably guided by a rear wall 15 and by a removable front wall 16. Action support 10 is normally held under tension by a spring 17 which bears against one of the end members 18 of the piano frame work. By means of this spring 17, support 10 is held under tension against a side member opposite member 18, which opposite side member is not illustrated.

At the bottom face of support 10, there is provided at the far side thereof, a slot 19 which is adapted to accommodate the head of lever portion 20 of what is known as "grand lever" 21, which latter is pivoted at 22.

Lever portion or lever member 20 is plainly illustrated in Fig. 4; it will be seen that this lever portion is provided at its upper end with an enlargement or head 23, adapted to engage the right-hand face (looking at Fig. 1) of slot 19, 10 and to move action support 10 in right-hand direction, when the lever is operated. The shifting of the support, and thereby of the entire action of the grand piano, is required for the purpose of playing "pianissimo". In order to thus shift 15 the action, the left-hand pedal of the piano, with which all "grands" are provided, is depressed. Such pedal is diagrammatically illustrated in Fig. 1, and is indicated at 24.

The pedal is pivoted at 25 and will lift, when 20 depressed, an action rod 26 which is suitably guided (not shown) so as to engage a flat enlargement 27 of "grand lever" 21.

By the upward movement of rod 26, grand lever end 27 is lifted, and causes lever portion 25 20 to swing to the right. The swinging movement of lever portion 20 causes the shift of action support 10, whereby the hammers (not shown) of the piano action are shifted about one-eighth of an inch. The hammers, when played while pedal 30 24 is depressed, will strike only two strings, out of every tone group of three strings, of the upper register, and only one string, out of each tone group of two strings, of the middle register. Such shift, however, does not bring out of operating 35 proximity the hammers of the piano actions opposite the single strings of the lowest register, except that in some pianos, the shifting of the action causes the hammers to strike these single strings somewhat to one side, with the intention 40 of producing a tone of lesser volume or strength.

In new grand pianos, the co-action between spring 17, engaging the action support, and the arrangement of pedal 24, rod 26 and lever 21, is designed to normally maintain contact between 45 head 23 of lever portion 20 and the right-hand side or wall of slot 19. After continuous use of these instrumentalities, it will occur that head 23 will gradually recede from its normal, intended wall-contacting position, and will assume a position away from the right-hand wall of slot 19. This will cause an idling movement. When pedal 24 is actuated, lever 21 will cause head 23 to first idly move towards the right-hand wall of slot 19. When head 23 finally contacts the wall, 55

this will result in an audible, interfering noise. In order to overcome this most annoying noise, I provide in connection with head 23, a spring member 28, which is provided at one end with 5 a short head-engaging leg 29, two rounded ends, a connecting portion 30, which latter preferably conforms with the contour of head 23, and a free extension 31 which is adapted to constantly contact with the left-hand wall or side of slot 19, 10 and is designed to maintain an abutting contact between the right-hand face of head 23 and the right-hand wall of slot 19.

The construction of the spring member 28 is clearly illustrated in Figs. 4 and 5. Since the 15 right-hand face of head 23 of the lever is constantly held under tension against the right-hand wall of slot 19, when lever portion 20 is actuated, by way of pedal 24, no abutting noise can occur.

20 Spring 28 is preferably so constructed and arranged that it will forcibly engage all faces of head 23 when pressed over the latter into the position shown in Fig. 5. In the event, however, there should occur a formation of small spaces 25 between head 23 and spring member 28, such as illustrated in Fig. 6, I prefer to fill in the spaces, marked "S", by means of lead or any other substance so as to preclude any contact- or operating-noises which may be caused by the looseness 30 of spring 28.

From Fig. 3 it will be clearly observed that the 35 end portions 32 of slot 19 are flaring towards the back side of support 10. These flaring ends 32 of the slots are provided for the purpose of permitting a gradual engagement by the slot of the spring-equipped head 23 when the action support is inserted into its intended position shown in Fig. 2.

It will be also observed that that curved portion 40 of spring 28 from which extends free end 31 must be directed toward the front of the piano, (or the closed end of slot 19), so as to facilitate the insertion of support 10, and the gradual compression of free spring end 31.

45 While I have illustrated in the accompanying drawing only two specific forms of my invention, it is quite obvious that any other suitable means may be substituted, which will effectively urge lever head 23 against, and maintain it in contact 50 with one of the walls of slot 19 at all times, and which will prevent any free movement of lever portion 20, or its head 23, within slot 19 at all times, and which will effectively prevent operating noises, occurring normally through wear 55 and tear of the instrumentalities for momentarily or temporarily shifting the grand piano ac-

tion to a "pianissimo" position. I therefore reserve for myself the right to make such substitutions, changes or improvements in the present invention which will accomplish the aforesaid results, without departing from the broad scope 5 of my invention as defined in the annexed claim:

I claim:

1. In a mechanism for shifting the action of grand pianos by way of the action support, a 10 recess or slot provided in the latter for accommodating the actuating end of said mechanism, a pedal operated lever having an extension terminating in a flat, broad head and constituting the actuating end of the mechanism, said head extending into said recess or slot of the action support, a leaf spring looped partially about the head and having a portion extending away from the head, said spring being of sufficient strength and being so constructed and arranged as to 20 constantly force one face of the head against one wall of the recesses or slot, while the extending spring portion constantly bears against the opposite wall of the recess or slot, thereby preventing any play of the head within the recess or 25 slot in any direction in respect to the walls of the latter, which results in the elimination of contact noises.

2. The combination with an action support having a slot for accommodating the actuating 30 end of an action shifting mechanism, of a flat, broad head equipped with a leaf spring and forming the terminus of the actuating end of said mechanism, said head being disposed within the slot provided in said action support, said 35 leaf spring forcibly engaging the ends of the head and having a free extension in forcible contact with one wall of said slot, said extension forcibly urging said head into permanent contact with the opposite wall of the slot, whereby 40 a free movement of the head within the slot is effectively prevented for the purpose of eliminating contact noises.

3. In an action shifting mechanism, an actuating lever terminating in an elongated, broad 45 head adapted to extend into a slot provided in the action support, a leaf spring secured to the upper end of the head and provided with a free extension adapted to forcibly bear against one wall of the slot and simultaneously forcibly urge 50 the head into permanent contact with the opposite wall of the slot, thereby effectively preventing the head from moving in respect to the slot for the purpose of eliminating contact noises.

JULIUS TUSTY, SR.
